UNITED STATES PATENT OFFICE.

HARVEY F. GASKILL, OF LOCKPORT, NEW YORK.

TRIPLE-EXPANSION ENGINE.

SPECIFICATION forming part of Letters Patent No. 394,482, dated December 11, 1888.

Application filed June 4, 1888. Serial No. 275,921. (No model.)

To all whom it may concern:

Be it known that I, HARVEY F. GASKILL, of Lockport, New York, have invented certain new and useful Improvements in Triple-Expansion Engines, of which the following is a specification.

The main object of this invention is to construct an engine so that the steam-passages between the cylinders shall be short and direct, and so that receivers may be dispensed with. Other objects will be apparent from the subjoined description. To these ends I arrange my three grades of cylinders side by side, the intermediate-pressure cylinder being between the high pressure and the low pressure, and I connect their pistons in such manner that the pistons of the high and low pressure cylinders move together in the same direction, and the pistons of the intermediate-pressure cylinders move in the opposite direction. By this arrangement I am enabled to exhaust the steam directly from the end of the cylinder in which it has just done its work into the cylinder of the next succeeding grade, in which it has next to operate. The invention consists in this arrangement of the cylinders and in other devices and combinations, as recited in the claims at the end hereof.

In the accompanying drawings I have shown a three-cylinder triple-expansion pumping-engine containing my invention.

In the drawings, Figure 1 is a vertical section through the three cylinders. Fig. 2 is a transverse vertical section through the high-pressure cylinder. Fig. 3 is a similar section through the intermediate-pressure cylinder, and Fig. 4 is a similar section through the low-pressure cylinder.

In the several figures, 1 is the high-pressure cylinder; 2, its piston; 3, its piston-rod.

4 is the intermediate-pressure cylinder; 5, its piston; 6, its rod.

7 is the low-pressure cylinder; 8, its piston; 9, its piston-rod.

10 are the valves which I have indicated, but have not thought necessary to show in detail.

11 is the steam-pipe, through which steam is admitted to the high-pressure cylinder from the source of supply.

12 is the exhaust from the low-pressure cylinder to the condenser.

13 is a bell-crank beam oscillating about a center, 14, and having its upper end connected

by a suitable link, 15, to the piston-rod 3 of the high-pressure cylinder.

16 is a triangular beam oscillating about a center, 17, and connected by suitable links, 18 and 19, with the piston-rods of the low-pressure and intermediate-pressure cylinders, respectively. The lower end of beam 16 is connected to the lower end of beam 13 by a link, 20. The crank-shaft I have shown connected by a connecting-rod, 21, with beam 16. 60 65

22 is the fly-wheel on the crank-shaft.

The pumps I have shown as single-acting pumps, arranged one in line with the low-pressure cylinder and one in line with the intermediate-pressure cylinder, and operated by 70 direct connection from their piston-rods.

In operation, supposing the piston of the high-pressure cylinder to be moving on its downstroke, the steam in the lower end of that cylinder will pass directly into the lower 75 end of the intermediate-pressure cylinder 4 and force its piston 5 upward, and the steam remaining from the former stroke in the upper end of cylinder 4 will expand into the upper end of the low-pressure cylinder 7 and force 80 its piston 8 downward, and the steam remaining in the lower end of piston 7 from the last preceding stroke will be exhausted at 12. Thus it will be seen that I expand the steam from one cylinder into the next lower grade 85 through the shortest possible passage, the passage being only long enough to go through the walls of the cylinders and have a controlling-valve.

What I claim is—

1. The combination, substantially as set forth, of the high, intermediate, and low pressure cylinders arranged side by side, with their pistons moving synchronously together, the intermediate piston moving in the opposite 95 direction to the others, a beam connected to two of said pistons, a second beam connected to the third piston, and a connection between said beams to insure their oscillating in unison.

2. The combination, substantially as set forth, of the high-pressure cylinder, the beam 13, with which it is connected, the intermediate and low pressure cylinders, the beam 16, with which they are connected, and the link 105 connecting said two beams.

HARVEY F. GASKILL.
